(57) **CLAIM**

The ornamental design for a screened enclosure water passageway, as shown and described.

DESCRIPTION

FIG. 1 is a front elevational view of the design. The existing frame is shown in broken line and is disclaimed as a part of the invention.

FIG. 2 is a rear elevational view thereof;

FIG. 3 is a right side elevational view thereof;

FIG. 4 is a left side elevational view thereof, with the passageway in a closed position, showing the position lock in the stored position;

FIG. 5 is a top plan view thereof;

FIG. 6 is a bottom plan view thereof; and,

FIG. 7 is a perspective view, showing the door passageway in the open position, and held by the latch in the open position.
